HUGO GROSS, OF MARTINSVILLE, NEW JERSEY

SAFETY DOOR FOR SWITCHBOARDS

Application filed November 22, 1927. Serial No. 234,953.

This invention relates to electric switches or fuse panels in general, and particularly to their closure.

One of the objects of this invention is to provide a door for the panel which may not be operated when the switch of the panel is in its circuit closing position, and which door may be opened only when the switch is in its circuit breaking position, thereby preventing any danger connected with handling fuses or switches within the panel while current is passing through.

Another object of my invention is to provide such safety door with a locking mechanism, the operation of which depends upon the operation of a switch handle operating the switch in the panel.

The foregoing and further objects will be more fully apparent from the following description and the accompanying drawings, forming part of this disclosure, and in which

Figure 1 represents a back view of the panel closure,

Figure 2 is a cross sectional view, taken on line 2—2 of Figure 1,

Figure 3 is a similar back view of the panel closure, showing the door opening mechanism in its unlocking position, and

Figure 4 is a cross sectional view, taken on line 4—4 of Figure 3.

Referring to the drawings, numeral 10 denotes the permanent closure portion of the panel which is fastened to the wall or over a panel mounted on a stand. Actually only 35 the front portion of the permanent panel closure is shown, as it is obvious that its form may be changed in accordance with the form of the panel mounting.

40 Fixedly attached to the permanent closure part is a bracket 11, which supports at 12 a switch lever 13. This lever is provided at 14 and 15 with abutments adapted to engage corresponding abutments 16 and 17, provided on bracket 11, which abutments limit 45 the swinging movement of handle 13. At 18, a bar 19 is hingedly attached to the handle 13, and is provided with a notch 20, the purpose of which will be explained presently.

50 Bar 19 serves as connecting rod between

handle 13 and the switch lever mounted within the panel, (not shown), and the movement of the handle 13 controls the position of the switch lever. Thus, when the lever is pulled to its extreme "out" position, the 55 switch lever disengages the switch mounting and thereby breaks the current. When the handle 13 is pushed into the inward most position, bar 19 causes the switch lever to make contact and thereby closes the circuit. 60

On the inner side of the permanent closure 10 and opposite bracket 11, there is provided a housing 21, in which is mounted a swinging 65 detent 22, adapted to register with and engage notch 20 of bar 19. At the lower portion of the detent are provided teeth 23. A pawl 24, normally placed against teeth 23 of the detent 22, by spring 25, is adapted to hold detent 22 in its engaging position, as shown in Figure 3.

Hingedly connected at 26 with the permanent closure, is a door or operative closure 27, which is adapted to swing in the disc from the panel mounting. Associated with this closure is a locking arrangement consisting 7 of a sliding bar 28, guided in its travel by two slots 29 and 30, engaging pins or bolts 31. The upper end of bar 28 is provided with a toothed extension 32, which is adapted to engage the teeth 23, of detent 22.

A transverse slot 33 is provided in bar 28 and is engaged by pin 34, eccentrically mounted on a disc 35, operable by wing knob 36. The operative closure 27 is prevented from swinging inwards by means of washers 37, 80 shown plainly in Figures 2 and 3.

Operation

When door 27 is in its closed position, and when handle 13 is in its inward position, 90 shown in Figure 2, bar 28 cannot be moved downwards, by turning knob 36, for the reason that teeth 23, of the detent, engage the teeth of extension 32, and the detent is prevented from turning since its edge 38 engages the full face of the bar 19.

When handle 13 is swung into outward position, as shown in Figure 4, so that its abutments 15 and 17 contact, bar 19 is brought into a position where notch 20 permits the 95

swinging movement of detent 22. It is then possible to turn knob 36 and thereby move slide 28 in downward direction, so that its upper end 32 clears the edge formed between the permanent and operative closures, as clearly seen in Figure 3. Now the door, or operative closure 27, may be readily swung outwards.

When it is desired to close door 27, first knob 36, is operated and slide 28 is brought with its toothed end against the lower edge of pawl 24. By so doing, the pawl is pushed out of engagement with the teeth of detent 22, and the teeth of extension 32 cause the detent 22 to turn in clockwise direction until it clears bar 19. Then lever 13 is brought into the inward position, shown in Figure 2, and renders the locking device of the door inoperative.

While I have shown specific forms of my device, be it understood that changes and improvements may be made thereon without departing from the broad scope of this invention, for which I claim:—

1. In combination with an electric switch or fuse panel, a permanent closure, an operative closure hingedly associated therewith, a pivoted switch handle mounted on said permanent closure and having means for limiting its swinging motion, a bar hinged to said handle and passing through said permanent closure into the interior of the panel and adapted to engage a switch lever thereon and capable of a reciprocating motion imparted thereto by said handle, a detent mechanism arranged below said bar and attached to said permanent closure, and consisting of a spring controlled detent adapted to swing into and out of the path of said bar, an opening and closing device mounted on said operative closure and having means for operating said detent, the latter having a housing, said operating means of said opening and closing device adapted, when engaged by said engaging means of said detent, to assume a position between said housing and the inner face of said permanent closure, thus preventing the operative closure from opening, said bar provided with a notch adapted to receive and permit the operation of said detent, when the bar is in its outward position, that is when the handle is pulled to its extreme "out" position, thus permitting the opening of said operative closure, said bar preventing the operation of the detent when in its inward position, that is when the handle is pushed to its extreme "in" position, thereby causing the engaging means of said detent to hold said opening and closing means in its closing position, thus preventing said operative closure from opening.

2. The combination with a closure for electric devices, composed of a stationary casing and a door hingedly connected therewith, of an operating lever pivotally mounted with-

out, and associated with said casing, an operating bar hingedly connected with said lever and extending into said casing and provided with a notch at its lower face, operation limiting means provided with said lever and governing the travel of said bar, and therefore its notch, a detent mechanism attached at the inner face of said casing and comprising a detent operative in a plane transverse the path of operation of said bar, and adapted to either engage said notch, or the solid side face of said bar, depending upon the position of the latter relative to said detent, detent locking means forming a part of said mechanism, and comprising a spring operated pawl adapted to engage and keep said detent in a position when it engages said bar notch, a detent operating device associated with said door and comprising a sliding bar at the inner face of said door, sliding bar actuating means engaging said bar and extending through and operative from without said door, said sliding bar provided with means for dislodging said pawl from engagement with said detent and for engaging and operating the latter so as to bring it in a position ready to engage the solid side face of said lever bar, said sliding bar forming, when engaging said detent, a closure for said door.

Signed at New York in the county of New York and State of New York this 15th day of November, A. D. 1927.
